UNITED STATES PATENT OFFICE

LEVI WESTGAARD, OF SEATTLE, WASHINGTON

PAPER BAG HOLDER

Application filed May 31, 1930. Serial No. 457,725.

My invention relates to bag holders of the type used for holding paper bags in retail stores and like places where large numbers of such bags are used.

5 A primary object of my invention is to provide a paper bag holder which is adapted to receive and hold a large number of paper bags in such a manner as to make the bags readily available for withdrawal one at a

10 time as said bags are used.

Other primary objects of the invention are to provide a paper bag holder of cheap and simple construction, which occupies little space in proportion to the number of bags it will hold; which is readily adaptable to various different locations; which may be hung on a wall or placed on a counter or secured in any convenient location; which permits the bags to be quickly and easily withdrawn by a

20 pull exerted from either end of the holder and which permits the bags to be quickly and easily loaded into the holder.

Paper bags of the form commonly used in retail stores are folded so that parts of the bottoms of said bags overlie the lower side portions of the same and extend upwardly and form tabs which may readily be grasped by the fingers. These folded bags are ordinarily placed one upon another in packages or bundles and when this is done the overlapped bottom portions have a greater thickness and cause the packages of bags to bulge at this location. The thickness at this point is further increased by the construction of the bag bottoms which are overlapped and glued. As these bags are used they are ordinarily picked, one at a time, off of the packages and it frequently happens that two or more of the bags will stick together or that several of the bags will be grasped by the fingers in attempting to pick up one bag.

It is an object of my invention to provide a bag holder within which a plurality of paper bags may be placed and held in such a manner that the upper end of the folded bottom of the outermost bag in the holder will always be caused to stand out away from the bag whereby it may readily be grasped and the outermost bag quickly and easily drawn out of the holder. The tab formed by the upper end of

the folded bag bottom is caused to stand outwardly from the outermost bag in the holder by providing means for exerting a pressure against the bundle of bags just above and just below the bulge formed by the upper ends of the folded bottom portions, or said ends may be caused to stand out by exerting a pressure above the bulge and holding the bags below the bulge or by exerting a pressure below the bulge and holding the bags above the bulge. The tendency to cause the tabs to stand out is increased by providing a bend in the main frame against which the bags rest, said bend being positioned so that the bottom ends of the bags may be pushed rearwardly farther than the upper portions of said bags thus increasing the bulging effect at the location of the overlapped bottom portions. This frame bend is particularly useful in making the tab portions of the bag bottoms stand out when only a few bags remain in the holder.

The above mentioned general objects of my invention, together with others inherent in the same, are attained by the device, illustrated in the following drawings, the same being preferred exemplary forms of embodiment of my invention, throughout which drawings like reference numerals indicate like parts;

Figure 1 is a front elevation of a bag holder constructed in accordance with my invention;

Fig. 2 is a side elevation of the same showing a number of paper bags held in operative position by said holder;

Fig. 3 is a perspective view of said holder without any bags therein;

Fig. 4 is a front elevation of a modified form of bag holder constructed in accordance with my invention;

Fig. 5 is a fragmentary front elevation of another modified form of bag holder constructed in accordance with my invention;

Fig. 6 is a fragmentary perspective view illustrating the manner in which the bag bottoms are usually folded; and

Fig. 7 is a fragmentary view in front elevation of an alternative form of the invention in which the cross bars for exerting a pressure against the bags below and above the bag

bottoms are connected with separate side-arms.

Figs. 1 to 3 show a paper bag holder preferably formed of wire and embodying a main frame arranged to be hung on a wall or placed on a counter or other fixed support, and a bag retaining frame resiliently connected with said main frame and arranged to yieldingly press a bundle of bags against 10 said main frame.

The main frame portion comprises two frame members 6 bent outwardly at their bottom end to form a bottom shelf or support which extends at right angles to said frame 15 members 6 and is arranged to support a bunch or bundle of paper bags 7 as shown in Fig. 2. The frame members 6 are bent rearwardly as at 6' to increase the bending effect of the bags at the location of the more bulky 20 bottom portions of said bags. The bottom shelf embodies two side arms 8 which are connected with the side members 6, two inwardly and rearwardly inclined members 9 and a downwardly bent loop portion 10 25 which is disposed in the common plane of the side members 6 and arranged to be secured to a wall as by a screw or nail, not shown. An extension member 11 of substantially U-shape rests on the inclined members 30 9 of the base and has its two ends bent to form loops 12 which extend around and slidably engage the side arms 8. The extension member 11 is shown in retracted position in Figs. 2 and 3 but it may be extended or drawn out- 35 wardly to support an unusually large bundle of bags.

Toward their upper ends the side members 6 are bent outwardly as at 13 then upwardly as at 14 and are thence bent inwardly as at 40 15 to form a support which extends crosswise of the top of the frame. A loop 16 is provided in the cross bar portion 15 to facilitate securing the main frame to a support.

The tops of the bags are prevented from 45 leaning outwardly by a retaining member embodying a downwardly bent portion 17 connected with portions 18 which diverge and extend rearwardly and which are bent to form loops 19 around the frame portions 14 and which thence extend downwardly in front of, and past the frame portions 13 and have other loops 20 on their bottom ends which slidably embrace the side members 6. At the location where they cross the 50 portions 13 the downwardly extending parts are bent as at 21 into a wave like form to afford notches which engage the frame portions 13 and hold the bag top retaining members in any desired adjusted position. This makes it 55 possible to move the bag top retaining member up and down to receive bags of different size.

For holding the lower ends of the bags inwardly against the main frame I provide 60 an open rectangular yoke having an upper

cross piece 22 arranged to extend across the bags just above the upper edge of the folded bottoms 23 of said bags and a lower cross bar 24 arranged to extend across the lower ends of the bags, and having two side pieces 25 each provided with a loop 26 which is formed midway between the two bars 22 and 24. The bottom cross bar 24 is preferably 70 in the form of a roller so that the bags will be more easily drawn out from under said 75 cross bar.

The yoke 22, 24, 25 is held in place by a resilient member embodying two side arms 27 having rearwardly bent ends 28 which engage within the loops 26 in the sides 25 of the 80 yokes. The side arms 27 are bent to form spring coils 29 and, above said spring coils, said side arms extend upwardly past the rear of the portions 13 and through the elongated loops 19 and thence are hooked over the top frame bar 15 as shown at 30 and are connected with each other by a cross member 31. The side arms 27 thus serve to press the yoke against the bags at all times and the yoke is free to tilt and conform to the shape of 85 the pack of bags so that substantially the same pressure is exerted by the top and bottom bars 22 and 24. The top bar 22 engages the bags above the top end of the folded bottom portions 23 of the bags and as said bags 90 have more plies of paper and are more bulky at the location of these bag bottoms 23 the upper end of the bottom of the outermost bag will always stand out where it may readily be grasped to pull the bag out. The yoke 22, 24, 25 will automatically adjust itself to a 95 thick or to a thin pack of bags and will maintain an even pressure against the bags until the last bag has been pulled out. The yoke may be quickly and easily removed to facilitate loading or insertion of the bags, by slipping the rearwardly bent end portions 28 out of the loops 26 in the sides of said yoke. If desired the bags may be inserted or loaded 100 by pulling the yoke outwardly without detaching said yoke.

In Fig. 4 I have shown an alternative form of the invention in which the main frame is formed of two spaced apart parallel bars 32 extended forwardly and connected at their bottom to afford a shelf 33 and extending outwardly toward their upper ends as at 34 and thence upwardly as at 35 and thence across the top end of the frame as at 36. Hangers 37 and 38, preferably of sheet metal, are secured to this main frame at the top and bottom respectively. An outwardly and downwardly extending retaining member 39 is provided at the top of the frame and this retaining member 39 is looped as at 40 over the top cross bar portion 36 near the outer ends of said cross bar portion and is thence extended downwardly to form two pressure arms 41 which are bent rearwardly at their bottom ends 42 and engage within loops 26 on the 110 115 120 125 130

sides of a yoke which is identical with the yoke 22, 24, 26, shown in Figs. 1 to 3. The pressure arms 41 are urged toward the main frame by two torsion springs 43 which are wound on the top cross bar 36 of the frame and each have one end 44 which extends downwardly and exerts a pressure against the adjacent pressure arm 41 and another end 44' which extends downwardly and is hooked under the frame portion 34. The operation of this device is substantially the same as the operation of the device shown in Figs. 1, 2 and 3.

In Fig. 5 I have shown a fragmentary view of another alternative form of my invention in which the detachable floating yoke for holding the bottoms of the bags is dispensed with two cross bars 45 and 46 which are rigid with the pressure arms 47 are provided in place of said yoke. These bars 44 and 45 do not automatically maintain an equal pressure on the bags above and below the bottom tab portions 23 for all conditions of loading as the floating yoke does, but they will operate successfully within a limited range of loading. When a large number of bags are in this holder the upper pressure bar 45 will press against the bags above the bottom tabs while the lower pressure bar will function as a holding means for the bottoms of the bags, but when only a few bags are in the holder, then the lower bar 46 may press against the bags and the upper bar may only act as a holding member. In all other features, except the bars 44 and 45, the holder shown in Fig. 5 may be the same as the holder shown in Fig. 4, or the same as the holder shown in Figs. 1 to 3 and may function in the same manner.

In Fig. 7 I have shown a fragmentary view of still another alternative form of the invention in which the upper presser bar 50 is connected with one set of side arms 51, only one of which is shown, and the lower presser bar 52 is connected with a different set of side arms 53. In this form each of the presser bars is resiliently and independently supported and is totally disconnected from the other side arm.

Obviously, changes may be made in the forms, dimensions and arrangement of the parts of my invention, without departing from the principle thereof, the above setting forth only preferred forms of embodiment.

I claim:

1. A paper bag holder embodying a frame for receiving a plurality of bags, each of the bags having folded bottoms forming a tab extending toward the upper end of the bag on the side of the bag which is to be turned outwardly in said frame, the folded bottoms affording greater thickness and causing the bags to bulge at this location; a presser bar adapted to extend across the bags just above the upper end of the tabs and adapted

to press the bags toward said frame; another presser bar adapted to extend across the bottom ends of the bags, forming between said two presser bars an open portion through which the tabs extend, whereby the tab formed by the bottom of the outermost bag may be caused to stand outwardly away from the bag and the said bag may be withdrawn out through said open portion.

2. A paper bag holder embodying a frame for receiving a plurality of paper bags, each of the bags having a folded bottom forming a tab extending toward the upper end of the bag on the side of the bag which is to be turned outwardly in said frame, the folded bottoms affording greater thickness and causing the bags to bulge at this location; resilient presser arms positioned at the sides of said frame and adapted to extend outside of and parallel to the sides of the bags; and two spaced apart presser bars secured to said presser arms and extending crosswise of the frame adapted to engage the bags at respective locations, just above and just below said bottom tab portions, thereby forming between said presser bars an open portion into which extends the said tabs, whereby the tab of the outermost bag may be caused to extend outwardly away from the bag and said outer-most bag withdrawn through said open portion.

3. A paper bag holder embodying a frame for receiving a plurality of paper bags, each of the bags having a folded bottom portion forming a tab extending toward the upper end of the bag on the side of the bag which is to be turned outermost in the holder; and a floating yoke member adapted to be resiliently held and pressed against the outermost side of the bags with two cross bars of the yoke extending crosswise of the bags just above the tabs and near the bottom ends of the bags respectively and the end members of the yoke adapted to extend outside of and parallel to the sides of the bags, whereby the tab of the outer-most bag may be caused to extend outwardly away from the bag and said outer-most bag may be withdrawn out through said open portion.

4. A paper bag holder embodying a frame for receiving a plurality of paper bags, each of the bags having a folded bottom portion forming a tab extending toward the upper end of the bag on the side of the bag which is to be turned outermost in the holder; a floating yoke member having two spaced apart presser bars adapted to extend across the bags just above the tabs and near the bottom ends of the bags respectively said yoke also having two end members adapted to extend outside of and parallel to the sides of the bags; and resilient means detachably engaging said yoke member and adapted to press the same against the bags, whereby the outermost bag may be grasped and drawn

outwardly from the holder between the two spaced apart presser bars of the yoke.

5. A paper bag holder embodying a frame for receiving a plurality of paper bags, each of the bags having a folded bottom portion forming a tab extending toward the upper end of the bag on the side of the bag which is to be turned outermost in the holder; resilient presser arms connected with the upper 10 end of said frame and extending downwardly along the sides of the same; and a yoke member having a pivotal connection with said presser arms, said yoke member having two spaced apart presser bars adapted to extend across the bags near the bottom of the bags and just above the upper ends of the tabs respectively for pressing the bags against said frame and causing the tab on the outer-most bag to stand away from the 20 bag, said yoke also having two end members adapted to extend outside of and parallel to the sides of the bags whereby the outermost bag may be grasped and drawn outwardly from the holder between the two spaced apart presser bars.

6. A paper bag holder embodying main frame means; a support extending outwardly from the bottom end of said main frame means; a bag retaining member extending 30 outwardly from the upper end of said main frame means; downwardly extending retaining means on the outer end of said bag retaining member, said frame and said support and said bag retaining member serving to receive a plurality of paper bags having folded bottoms which afford upwardly projecting tabs; two presser arms connected with the upper end of said main frame means and extending downwardly along the sides thereof; and a floating yoke member pivotally and detachably connected with the lower ends of said presser arms, said yoke member having two presser bars extending across the bottom portions of the bags in said frame just 40 above said tabs and below said tabs respectively and said yoke having two end members adapted to extend outside of and parallel to the sides of the bags, whereby the tab of the outer-most bag may be caused to extend outwardly away from the bag and said outer-most bag withdrawn through said open portion.

50 In witness whereof, I hereunto subscribe my name this 24th day of May, 1930.

55 LEVI WESTGAARD.
